(57) **CLAIM**

The ornamental design for a molded worm fishing lure, as shown and described.

DESCRIPTION

FIG. 1 is a front elevation view of a molded worm fishing lure embodying my design, which is identical to right and left side elevation views;

FIG. 2 is a rear elevation view of the molded worm fishing lure, which is identical to right and left side elevation views;

FIG. 3 is a top view of the molded worm fishing lure; and, FIG. 4 is a bottom view of the molded worm fishing lure. The broken lines are shown for illustrative purposes only and form no part of the claimed design.
